TYPEWRITING MACHINE

David Y. Read, New York, N. Y., assignor of one-fourth to Jessie P. Grandy, and one-fourth to Henry H. Snelling, both of Washington, D. C.

Original application November 7, 1932, Serial No. 641,630. Divided and this application May 17, 1937, Serial No. 143,186

11 Claims. (Cl. 197—66)

This invention relates to typewriting and calculating machines and has for its object the improvement of the carriage operating mechanism.

A particular object of the invention is the provision of a simple motor driven carriage return for typewriters.

This is a division of my application, Serial No. 641,630 filed November 7, 1932, now Patent Number 2,114,270 dated April 12, 1938.

10 Figure 1 is a fragmentary vertical transverse section of a machine taken through the motor return shaft.

Figure 2 is a side elevation of the parts shown in Figure 1, this part being taken at 90° to Figure 1.

15 Figure 3 is a top plan view of the parts shown in Figures 1 and 2.

Figure 4 is a plan view in an inclined plane of the snap spring for holding the motor shaft 20 sleeve in its elevated position.

Figure 5 is a side elevation of the carriage rail partly broken away.

25 *Motor carriage return.*—While naturally the typewriter carriage can be returned by hand it is convenient to provide means to save the operator this extra exertion. I therefore provide a carriage motor return key 360 mounted rather high above the level of the horizontal portion of its lever 361 so that the key itself may be in line 30 with the letter keys and the lever may be below all of the letter key bars and also the space bar levers. The lever 361 is pivoted at 362 between a pair of depending ears 363 on the central bracket 364 of a casting 365 which supports most of 35 the motor carriage return mechanism.

A downwardly projecting lug 367 is bored on opposite sides as at 368 to receive the ends 369 of a double convex spring 370 which acts as a toggle to keep the rear end of the lever 361 either 40 all the way up or all the way down. The center of this spring 370 is received in a kerf 371 in the lever 361 which passes outside or just to the right of the vertical motor shaft 377 having on its bottom a gear 378 receiving power from a motor 45 shaft 379 thru a worm 380. A sleeve journaled in the central bracket 364 and also in an upper bracket 383 of the casting 365 is splined to the constantly revolving vertical shaft 377 by means of a rounded end screw 384 which fits loosely in 50 a slot 385 in the shaft 377 so that while the sleeve 381 is forced to revolve with the shaft 377 it may move vertically with respect to it when the lever 361 is moved about its pivot 362 since this lever lies tight to the shaft 377 and engages the bottom 55 of the sleeve as best seen in Figures 1 and 2.

Fast to the top of the sleeve 381 is a head 386 having a cooperating member or collar 387, forming with it a clutch. The head is fast to the sleeve and forms its support, this clutch element having a bearing on the top surface of the upper bracket 383 of the casting 365 which by the way is secured to the lower frame or bed of the machine so as to be readily detachable therefrom, preferably from the outside as for example, by the screws 389. The collar 387 or upper portion of the clutch is guided and retained by the shaft 377 and is normally held in place by gravity only.

The carriage return drum 274 is journaled as at 390 to the underneath side of the table 86 15 which is the top plate of the hood and this drum has teeth 391 engageable with similar cooperating teeth 393 on the collar 387. The drum 274 has fast to its peripheral groove a cord 273 which passes over a pulley 394 journaled to the rail 111 20 and has its free end attached to the blade 262 which is carried by the rail but has a slight movement with respect thereto for a purpose fully explained and claimed in my Patent No. 1,888,144, dated November 15, 1932. The function 25 of the spiral spring 395 on the shaft 390 and connected to the pulley 394 is merely to keep the cord 273 taut at all times and the spring is preferably a small hair spring offering no appreciable obstruction to the movement of the 30 carriage.

The operation of the motor carriage return is as follows: The key 360 is pressed down. The rear end of the motor carriage return key lever 361 compresses the spring 370 while raising the 35 sleeve 381. When the key 360 is pressed half or more of its travel the spring 370 starts to expand and forces the sleeve 381 to its upper limit of travel, carrying the collar 387 into contact with the drum. The rotation of the shaft and sleeve 40 is now transmitted to the drum which winds up the cord 273 until the carriage movement is stopped. The shaft 377 however is constantly revolving and since the collar 387, which is not fast to the shaft 377 in any way, can no longer 45 revolve with the shaft 377 since the cord 273 is now taut, the steep angular faces between the head and collar cam down the sleeve which is held up only by the spring 370, and which is purposely relatively weak. This action lowers the 50 head 386 and the height of the teeth in the clutch is sufficient to carry the spring 370 past the so-called dead line position considering it as a toggle and the spring 370 therefore snaps the lever 361 back to normal position. The collar 55

387 which now has nothing to keep it aloft falls by gravity with the sleeve 381 into the position shown in Figures 1 and 2.

The drawing up or winding of the cord 273 on the drum 274 accomplishes two substantially simultaneous motions as in an ordinary typewriter, one the return of the carriage and the other the line spacing operation. In an ordinary typewriter however these two operations, while substantially simultaneous, may take place one before the other and in any event the line spacing is positively moved, whereas in the present machine the line space is merely set and a spring shown in my Patent No. 1,888,144 dated November 15, 1932 performs the actual line spacing of the paper holder only after the cord 273 is released. The return of the carriage is had since the pulley 394 is fast to the carriage rail 111 and the line spacing setting is had since the blade 262 is pulled to the left with respect to the rail as viewed by the operator.

Considering now Figure 5, the winding of the drum 274 moves the rail 111 to the right as viewed from the operator. The blade 262 is moved generally in the same direction since it is secured to the carriage rail frame by the bracket pins 271 but in view of the connections, as best seen in Figure 3 the blade is given a reverse movement with respect to the rail during the motor carriage return operation. This causes the blade rack teeth 268 to turn the gear 121 and consequently the rod 118 in a clockwise direction as seen in Figure 5 which may operate linkage for any desired purpose, for example to set the line spacing mechanism as fully described in my Patent No. 1,888,144 dated November 15, 1932; this linkage is not shown herein because it is only incidental to the present invention. In other words as far as the carriage return is involved the free end of the cord 273 might be connected directly to the rail.

What I claim is:

1. In a motor driven carriage return mechanism, a constantly driven shaft, a sleeve slidably splined thereto, a carriage return drum adjacent the sleeve, a clutch actuated by shifting of the sleeve for operatively connecting the drum and sleeve, means controlled by the operator for shifting the sleeve to clutching position, and additional means, cooperating with the last mentioned means and operative in response to a predetermined load on the clutch, for automatically disconnecting the clutch and drum when said drum is checked.

55 2. In a carriage motor return, in combination, a rotatable member connected to a carriage to move the same, a drive shaft, a clutch element carried by said rotatable member, connecting means slidably spined to said shaft, a second 60 clutch element carried by said connecting means, means for shifting said connecting means and thereby moving said elements into clutching position to connect said shaft and rotatable member, and means for automatically separating said 65 clutch elements in response to increase in load produced when the rotatable member is checked, said connecting means including load responsive means for initiating the separating movement of said clutch elements.

70 3. The device of claim 1 in which said additional means includes a snap over toggle spring for yieldingly holding the sleeve in clutching or disconnecting position.

4. The device of claim 1 in which the clutch 75 is in three parts, one secured to the drum, a

second part secured to the sleeve and the third part is between the two clutch parts just mentioned, said third part engageable with the first part to drive the same and having an inclined plane driving connection with the second part and designed to force the sleeve toward disconnecting position in response to a stopping of the drum.

5 5. In a typewriting machine motor driven carriage return mechanism, a carriage, a drum operatively connected to the carriage, a motor driven shaft, means including a clutch for connecting said drum and shaft to return the carriage, a key depressible for moving the clutch to operative position, yielding snap over toggle means for retaining the key in depressed position and the clutch in clutched position during movement of said drum, and means in the clutch and cooperating with said yielding means for automatically restoring the clutch and 10 key to normal position upon checking of the carriage return movement.

15 6. In a typewriter, a carriage, a drum, a band connecting said drum and carriage to return the carriage, a constantly revolving shaft, a clutch 25 element slidably supported on said shaft but constrained to revolve with it, a loose collar having clutch engagement with the drum and with the clutch element separately and with both together, means for shifting the clutch element and thereby moving the collar into engagement with the drum to cause the drum to be driven by said shaft, said means including mechanism for yieldingly holding said elements in such position, the engagement between the clutch element on the 30 shaft and the collar including steeply sloping teeth so that the collar and clutch element are disconnected upon the stopping of the drum due to an obstruction to the carriage.

35 7. The device of claim 6 in which the clutch element is fast to a sleeve which surrounds the shaft, and the collar is supported by the clutch element and guided by the shaft.

40 8. The device of claim 6 in which said shifting means includes a motor carriage return control lever for raising the collar into engagement with the drum, snap over toggle means for holding said lever in collar elevated position and for restoring said lever when the clutch elements are disconnected.

45 9. In combination, a three-piece clutch, an elongated flexible carriage return member secured to one of said pieces, a motor, a carriage return key, mechanism movable by said key to connect the motor and member through said clutch to move the member in carriage return direction, two of the pieces of the clutch having cooperating steep angular faces whereby the clutch pieces are quickly separated when the member is locked against rotation, a snap over toggle 50 spring positioned to hold the key in clutching position or in normal position, said cooperating faces being dimensioned to move the key past mid position in separating said clutch pieces whereby the toggle then throws the key to normal 55 position thereby disconnecting the motor from the carriage return member.

60 10. In a motor driven carriage return mechanism, a constantly driven shaft, a sleeve slidably splined thereto and having a normal position and a clutching position, a carriage return drum adjacent the sleeve, a clutch for operatively connecting the drum and sleeve, carriage return key means for shifting the sleeve to clutching position, and declutching means responsive to a pre- 65

- determined clutch load and cooperating with the key means for automatically disconnecting the clutch and drum when said drum is checked and for returning all the parts to normal position, a 5 part of said declutching means consisting of inclined plane elements for transmitting normal torque from the shaft to the clutch and for initiating the disconnecting action in response to abnormal load.
- 10 11. In combination, a carriage, an elongated flexible member for returning the carriage, a drum to which the member is attached, teeth on said drum, a collar having teeth cooperating with the drum teeth, a head, cooperating steep angular teeth on said head and collar, a motor driven shaft coaxial with the drum, collar, and head, a splined connection between the shaft and head for winding the member on the drum 5 when the head is moved toward the drum, a carriage return key for moving the head toward the drum, and means for returning the parts to initial position when the resistance to rotation of the drum causes the steep angular teeth to 10 separate the head and collar.
